UNITED STATES PATENT OFFICE.

JULIUS RITTER, JR., OF RACINE, WISCONSIN, ASSIGNOR TO HARTMANN TRUNK COMPANY, OF RACINE, WISCONSIN, A CORPORATION OF WISCONSIN.

CLAMPING LOCK.

Application filed July 7, 1923. Serial No. 650,192.

This invention relates to improvements in clamping locks, more particularly adapted for trunk use.

Hasp locks are usually used on trunks, and when the trunks are packed, it is quite difficult to draw the trunk cover or sections together sufficiently to permit the hasp member to be swung to closed position to permit locking.

10 It is one of the objects of the present invention to overcome the above mentioned objectionable feature and provide a clamping lock in which the hasp member thereof may be used as a lever to clampingly draw the 15 two parts of the trunk together to permit the easy locking thereof.

A further object of the invention is to provide a clamping lock which when in locked position relieves the locking member of the 20 strain of holding the trunk parts together.

A further object of the invention is to provide a clamping lock which is also adapted to wedgingly force the cover to open position in a very simple manner.

25 A further object of the invention is to provide a clamping lock having means for sealing the lock when in closed position.

A further object of the invention is to provide a clamping lock which is of simple 30 construction, is strong and durable and is well adapted for the purpose described.

With the above and other objects in view, the invention consists of the improved clamping lock and its parts and combinations as 35 set forth in the claims, and all equivalents thereof.

In the accompanying drawing in which the same reference characters indicate the same parts in all of the views:

40 Fig. 1 is a front view of the upper portion of a wardrobe trunk provided with the improved clamping lock;

Fig. 2 is a vertical sectional view thereof showing the trunk cover in a position to 45 engage and clampingly draw the cover to a closed position to permit the easy insertion of the hasp member to its locked position; and

Fig. 3 is a vertical sectional view thereof 50 showing the hasp member in locked position.

Referring to the drawing, the numeral 5 indicates a wardrobe trunk section, 6 the top cover thereof, and 7 the improved clamping lock for locking the two parts together. Said lock comprises a hasp plate 8 adapted

to be fastened to the cover or one section of a trunk and to which is hinged one end portion of a link member 9. The outer end portion of said link is hinged to the hasp lock member 10 which is provided with a keyed lock 11 adapted to enter the locking recess 12 of the escutcheon plate 13 mounted on the trunk section 5. The hasp member 10 is provided with a U-shaped clamping extension 14 projecting from the inner end of the hasp member 10 which is positioned to engage the shoulder or hook-shaped end 15 forming part of the escutcheon plate 13, before mentioned. By engaging the U-shaped extension with the hook shaped end and then swinging the hasp member to its locked position, the cover or section will be clampingly drawn to its closed position with relation to the trunk section, and as shown in Figs. 2 and 3.

75 The escutcheon plate 13 is also provided with a stop hook portion 16 which is engaged by the U-shaped member of the hasp, and the hasp pressed upwardly when it is desired to force the cover to open position in case it will not open easily.

80 Trunks are at times shipped by express, and to do so it is necessary to seal the cover before the express company will accept shipment. To permit this, the escutcheon plate is provided with an outwardly projecting staple 17 which extends through an opening 18 formed in the hasp member 10 when the hasp member is in closed position. When thus positioned, a wire 19 may be passed 85 through the staple and the end portions of the wire sealed by a lead seal 20 in the usual manner.

90 From the foregoing description, it will be seen that the clamping lock is of very simple construction and is well adapted to clampingly draw the cover to closed position, or to force the cover to open position when desired.

95 What I claim as my invention is:

100 1. A clamping lock, comprising an escutcheon plate having hook like shoulders and a locking recess, a hasp plate, a link hinged at one end to the hasp plate, and a hasp member hinged at one end to the free end of the link and having a U-shaped extension at its hinged end engageable with one of the hook like shoulders to clampingly draw the hasp plate towards the escutcheon plate when the hasp member is swung to 105 110

locking position or engageable with the other hook like shoulder to separate the hasp plate from the escutcheon plate when the hasp member is swung away from its locking position, the said hasp member also having a locking portion which enters the locking recess of the escutcheon plate to lock the parts together.

2. A clamping lock, comprising an escutcheon plate having an upper and a lower hook like shoulder and a locking recess, a hasp plate, a link hinged at one end to the hasp plate and having inwardly extending side flanges, and a hasp member hinged at one end to the free end of the link, said hasp member also having an extension at its

hinged end engageable with the upper of the hook like shoulders to clampingly draw the hasp plate towards the escutcheon plate when the hasp member is swung to locking position or engageable with the lower of the hook like shoulders to separate the hasp plate from the escutcheon plate when the hasp member is swung away from its locking position, the said hasp member also having a locking portion which enters the locking recess of the escutcheon plate to lock the parts together. 20 25

In testimony whereof, I affix my signature.

JULIUS RITTER, JR.
